UNITED STATES PATENT OFFICE

160,345

HOBBYHORSE

Earl F. Shores, Los Angeles, Calif.

Application March 19, 1949, Serial No. 1,499

Term of patent 7 years

(Cl. D34—15)

To all whom it may concern:

Be it known that I, Earl F. Shores, a citizen of the United States, residing in Los Angeles, in the county of Los Angeles and State of California, have invented a new, original, and ornamental Design for a Hobbyhorse, of which the following is a specification, reference being had to the accompanying drawing, forming part thereof:

Fig. 1 is a perspective view of a hobbyhorse, showing my new design.

Figs. 2 and 3 are enlarged cross-sectional views, taken on the respective lines 2—2 and 3—3 of Fig. 1.

The dominant features of my design reside in the portions shown in full lines.

The opposite side of the hobbyhorse is substantially the same as the side shown in Fig. 1.

I claim:

The ornamental design for a hobbyhorse, substantially as shown and described.

EARL F. SHORES.
